United States Patent Office

S. J. MITCHELL, OF ST. LOUIS, MISSOURI.

Letters Patent No. 68,225, dated August 27, 1867.

IMPROVEMENT IN COTTON-BALE TIE.

The Schedule referred to in these Letters Patent and making part of the same.

TO ALL WHOM IT MAY CONCERN:

Be it known that I, S. J. MITCHELL, of St. Louis, in the county of St. Louis, and State of Missouri, have invented a new and useful Improvement in Cotton-Bale Ties; and I do hereby declare that the following is a full, clear, and exact description thereof, which will enable others skilled in the art to make and use the same, reference being had to the accompanying drawings, forming part of this specification, in which—

Figure 1 is an under side view of my improved bale-tie attached to an iron hoop as placed on a cotton-bale.

Figure 2 is a section through the hoop and tie, taken in the line *x x*, fig. 1.

Figure 3 is a section of the bale-tie detached.

Similar letters of reference indicate like parts.

This invention relates to an improved construction of a fastening for the ends of iron hoops to secure them on a cotton or other bale, and consists in a malleable cast-iron or other metal plate, having a slot in it wide and long enough to admit the two ends of a hoop side by side when inserted in the slot to secure them, and provided with a pin projection in the slot to pass through a hole to be made in one end of the hoop, and another pin projection on the under side of the plate to go through the other end of the hoop, when the ends are fastened, in order to secure and prevent them from slipping.

A is the metal plate, made thicker in the middle than at the ends, and having a cross-slot, *a*, extending from one side nearly across the plate, as shown in fig. 1. On the inside of the slot *a* is a projecting pin, *c*, on one wing, *d*, of the plate, and on the under side of the other wing *d'* is another projecting pin, *c'*, both of which pins pass through holes to be punched in the iron hoop *B*, as shown in fig. 2. The lap *e* of the hoop is introduced in slot *a* from the upper side of the plate *A*, and lies flat under the plate and the hoop next the bale to which it is attached; and the pin *c'* passes through a hole in the lap *e'*. The lap *e* on the other end of the hoop is introduced into the slot *a* from the under side of the plate, and lies flat on the upper side of the plate and the hoop, and the pin *d* passes through the lap *e* to hold it fast.

Having described my invention, I claim as new, and desire to secure by Letters Patent—

A cotton-bale tie, formed of a metal plate, *A*, having a slot, *a*, nearly across it, and the pins *c c'* on the wings *d d'*, constructed and operating as herein specified.

S. J. MITCHELL.
